UNITED STATES PATENT OFFICE.

GEORGE M. KEISER, OF CASS TOWNSHIP, SCHUYLKILL COUNTY, PENNSYLVANIA.

VALVE.

1,033,325.

Specification of Letters Patent. Patented July 23, 1912.

Application filed September 22, 1910. Serial No. 583,210.

To all whom it may concern:

Be it known that I, GEORGE M. KEISER, a citizen of the United States, residing at Cass township, in the county of Schuylkill and State of Pennsylvania, have invented new and useful Improvements in Valves, of which the following is a specification.

This invention relates to valves, more particularly to the seats thereof; and has for its prime object to provide a valve seat which will not be subject to rapid corrosion and erosion from the passage of fluid containing more or less acid and sulfur in solution, and small particles of coal, dirt, slate, culm and muck in suspension.

The valve seat is designed mainly but not exclusively to be used in pumps of all kinds and especially in such as are employed in anthracite and bituminous coal mines for pumping water therefrom which is more or less charged with acid and gritty substances that rapidly destroy the operating face of the valve seats and consequently produce leaking.

The valve seat of the present invention is provided with an opening or openings through which liquid passes, said opening or openings being surrounded by rings, bands, or belts of non-corrodible substance which is also practically immune from the erosive action of destructive substances contained in the water. These rings, bands, or belts are made flush with the valve seat against which the valve contacts fluid tight; and notwithstanding the fact that the surface of the valve seat over which the water flows is being destructively acted upon by the foreign substance contained in the passing water, the aforesaid rings being practically free or only slowly affected by said foreign substances the valve remains tight and its "life" greatly prolonged.

For a fuller and clearer understanding of the invention, attention is called to the following detailed description and the accompanying drawings in which,—

Figure 1 is a perspective view of the improved valve seat. Fig. 2, a plan view of the same. Fig. 3, a sectional view on the line 3—3 of Fig. 2, showing the valve in place, Fig. 4, an enlarged sectional view of a detail of the invention, and Figs. 5 and 6 are sectional views illustrating diagrammatically portions of two valve seats when subjected to water containing acid, or sulfur, or small particles of coal, dirt, muck,

etc., Fig. 5 showing a valve-seat in common use without the non-corrodible wear resisting inserts or packing rings.

In the drawing, 10 indicates the body of the valve-seat, here shown as of cylindrical form with an outwardly projecting flange 11 at one end and smooth and flat at its opposite end against which the valve 12 is adapted to seat. The valve-seat body 10 is hollow, open at its flanged end, and provided with a perforated head 13 at its opposite end against the outer surface of which the valve 12 seats as stated.

Through the axis of the head 13 in this type of valve is made a hole 14 in which the stem 15 of the valve 12 slides, while surrounding said hole are a plurality of other holes 16 for the escape of water when the valve is raised from its seat.

Formed in the head 12 in any suitable manner between the openings 16 and the peripheral surface of the body 10 is an annular groove 17 wider at the bottom than at the top or of dove-tail shape, as clearly shown in Fig. 4, into which is inserted a ring, band, or belt made of some non-corrodible wear resisting substance 18, such as lead, glass, wood, or other suitable material possessing the required properties to serve as a packing for the valve 12. A like annular groove 19 is made in the head 13 between the openings 16 and the central hole 14 for an insert or ring 20 similar to the ring 18 in the outer groove 17.

The inserts or packing rings 18 and 20 are preferably run into the grooves 17 and 19 when the nature of the material permits it to assume a fluid condition, and their exposed edges ground off flush with the face of the valve-seat, as shown in Figs. 1 and 3. By this method of inserting the packing material in the annular grooves, they are held tightly in place and will not work loose.

In action, when the valve 12 opens or is opened, water passes through the valve-seat body 10 in the direction indicated by the arrows and out of the openings 16. If any of the foreign elements noted above be in the water, destructive action on the metal composing the body will be set up and in a short time the valve seating surface of the head 12 will lose its smoothness and become uneven, and if not supplied with the packings, leakage will result when the valve closes, which will rapidly increase by the

erosive action of small particles of coal, dirt and muck in the water. See Fig. 5. When the wear resisting non-corrodible rings are employed, the destructive action 5 on the valve-seat body continues, but as said rings resist such wearing action, see Fig. 6, there will be no leakage when the valve closes, consequently the life of the valve-seat is extended. The normal wear 10 on the packing rings by the valve presents a surface of gradually increasing width and maintains a perfectly tight fit.

Attention is called to the fact that initially the faces of the valve seat and packing rings are in a common plane; when therefore the valve closes the force of said closure is distributed over the entire surface of the valve seat. Packing rings which project above the face of the valve seat are 15 known, but in such construction the valves on closing bear only on the packing rings, which latter are thus subjected to the hammering action of the valve which tends to break, spread and otherwise deform the 20 faces of said rings especially if made of a soft material, so that leakage past the valve will result. Now by making the packing rings flush with the faces of the valve they cannot be deformed when the valve closes 25 because the latter contacts simultaneously with the much greater area of the valve seat. The flow of water being deflected outwardly by the valve, wear on the valve seat caused by destructive elements in the water 30 is not the same throughout its entire surface, the greatest wear being between the openings 16 and the outer edge of the body 35. There will be less wear between the 40 said openings and least wear on the surface surrounded by or within the circle of the openings. From this it is evident that notwithstanding the fact that the face of

the valve seat may be worn away on each side of a packing ring between the openings and the outside of the body to such an extent that the packing ring at these points projects slightly above the valve seat, see Fig. 6, nevertheless the fact that the major portion of the valve seat remains practically unworn, such projecting portions of the 45 ring are not subjected to the hammer action of the valve and its bearing face thus remains true.

It is to be understood that the valve seat may have a single opening only and that 50 the valve may be supported otherwise than on a stem passing through the valve seat, as shown in the drawing, which form of construction is illustrative only of one type of valve to which the present invention may be 55 applied.

I claim:

A valve seat comprising a hollow body provided with a head at one end having an axial opening therethrough for a valve 60 stem, and a plurality of openings surrounding said axial opening for the passage of fluid, the outer face of said head forming of itself a fluid-tight seating surface for a valve, a ring of non-corrodible wear resisting material inserted in said face between the fluid openings and the perimeter of the valve seat, and a second similar ring surrounding the valve stem opening and within the fluid openings the surfaces of said 70 rings being flush with the seating surface. 75

In testimony whereof I have hereunto set my hand in presence of two subscribing witnesses.

GEORGE M. KEISER.
